UNITED STATES PATENT OFFICE.

REUBEN WIGHT, OF WESTFIELD, NEW YORK.

WEATHER-STRIP FOR DOORS.

Specification of Letters Patent No. 16,077, dated November 11, 1856.

To all whom it may concern:

Be it known that I, REUBEN WIGHT, of Westfield, in the county of Chautauqua and State of New York, have invented a new 5 and useful Improvement in Weather-Strips for Doors; and I do hereby declare that the following is a full, clear, and exact description of the construction and operation of the same, reference being had to the annexed 10 drawings, making part of this specification, and to the letters of reference marked thereon.

Similar letters refer to like parts in the various figures.

15 My invention consists in employing a metallic plate as an adjustable weather-strip, it being inserted in the bottom rail of the door, and concealed in front by a face-plate, and operated by a rack and segment lever 20 from the inside.

Figure 1, is a vertical cross-section of the bottom rail of an ordinary door.

A is the weather-strip, B the face-plate covering the weather-strip on the front or 25 outside of the door. The door is rabbeted about $\frac{1}{4}$ or $\frac{3}{8}$ of an inch deep, or a space equal to the thickness of the strip. The strip consists of a brass or iron casting, about two 30 inches in width, of a length corresponding to the width of the door; shown detached in Fig. 2. It may be made from $\frac{1}{8}$ to $\frac{1}{4}$ inch in thickness or heavier if required. This strip has at the center a vertical fillet or 35 projection C, Fig. 3, which fits in a corresponding groove in the face plate and forms a guide in which the strip moves. On the reverse side of the strip, is a vertical cog- 40 rack D, Fig. 2, with which the toothed segment E, Fig. 1 gears. This segment moves on the pin F, by the means of the lever handle G, which is a button having an internal screw fitting upon the screw H, of 45 the lever handle. The axis of this segment-lever is a small metallic plate I, attached to the inside of the door, through a slot in 50 which the lever passes. On each side of this slot are two ears, J, J, Fig. 4, raised about $\frac{3}{8}$ of an inch from the surface of the plate, forming cams. By loosening the button G, 55 by a turn with the hand, it allows the lever to be moved sufficiently to raise the strip clear of the threshold and allow the door

to swing. By this means the button is brought below the highest point, a, of the cam, as shown by the dotted lines, K, when, 55 by tightening the button again, the strip is rendered immovable.

For ordinary use in mild weather the strip is left raised and is therefore concealed from view, but in stormy weather or on closing 60 the door for the night, by raising the lever to the position shown in the drawings, the strip is drawn down tightly against the threshold, and by tightening the screw, secured in that position. Less than a single 65 revolution of the button is sufficient to tighten the screw. The threshold has a beveled rabbet L, and the strip a corresponding bevel by which the door is drawn closely to the jamb when the strip is thrown down. 70 There is a slot, M, through the face plate with a button N inserted by a screw in the strip from the outside of the door, this may be used as a means of raising the strip from the outside when the button on the lever is 75 left loose, or it may be dispensed with and the escutcheon, O, covers the hole. It forms not only a safeguard against rain, snow and cold air driving under the door, but a very effectual fastening against burglars. Act- 80 ing as a bolt, its line of bearing extends the whole width of the door, and for bank, store and shop doors one may also be attached at the top rendering the fastening doubly se- 85 cure, as the ordinary methods of disposing of locks and bolts are inoperative against it. But it is especially adapted to the doors of steamboats and other vessels. By placing a strip of india rubber on the threshold the weather strip may be made to fit so tightly 90 as to entirely exclude the most driving sea to which a vessel is exposed.

If desired, the face-plate B may be dis- 95 pensed with, and the strip made to work in a groove in the rail of the door so as to entirely conceal all parts, except the button and cams, on the inside, which may be made as ornamental as desired.

The model exhibits a door of $\frac{1}{2}$ inch thick- 100 ness. To adapt it to an inch and a half door the strip is cast with a ledge $\frac{1}{4}$ inch high b, Fig. 2, on which the teeth are cast, and for two inch doors, the lever plate, I, is mortised in, the mortise being covered by a metallic

frame P, Fig. 4, surrounding the plate, and leaving it recessed in, half an inch below the surface.

What I claim as my invention and for which I desire to secure Letters Patent, is— The adjustable weather strip A, operated by the segment-lever E, in connection with the movable button G, and the cams J J,

the whole constructed and arranged in the manner and for the purpose herein fully set forth.

REUBEN WIGHT.
